United States Patent Office

Des. 224,370
Patented July 18, 1972

224,370

TOTE BAG

Morris J. Berry, Brooklyn, N.Y., assignor to Fashioncraft-
Excello, Brooklyn, N.Y.

Filed Nov. 12, 1970, Ser. No. 25,946

Term of patent 14 years

Int. Cl. D3—01

U.S. Cl. D87—3

FIG. 1.

FIG. 2.

FIG. 3.

FIG. 4.

FIG. 5.

FIG. 1 is a front elevational view of a tote bag showing my new design;

FIG. 2 is a rear elevational view thereof;

FIG. 3 is a bottom plan view thereof;

FIG. 4 is a top plan view thereof, the handles being separated to reveal the closure; and

FIG. 5 is an elevational view of one side thereof, where the side opposite that disclosed is the same.

I claim:

The ornamental design for a tote bag, substantially as shown and described.
